CLAIM

I claim the ornamental design for an induction range, as shown and described.

DESCRIPTION

FIG. 1 is a top, front and right side perspective view of an induction range showing my new design;

FIG. 2 is a left side elevational view thereof;

FIG. 3 is a right side elevational view thereof;

FIG. 4 is a top plan view thereof;

FIG. 5 is a front elevational view thereof;

FIG. 6 is a bottom plan view thereof;

FIG. 7 is a rear elevational view thereof;

FIG. 8 is a top, front and right side perspective view of a second embodiment thereof;

FIG. 9 is a left side elevational view of FIG. 8;

FIG. 10 is a right side elevational view of FIG. 8;

FIG. 11 is a top plan view of FIG. 8;

FIG. 12 is a front elevational view of FIG. 8;

FIG. 13 is a bottom plan view of FIG. 8;

FIG. 14 is a rear elevational view of FIG. 8;

FIG. 15 is a top, front and right side perspective view of a third embodiment thereof; and,

FIG. 16 is a top, front and right side perspective view of a fourth embodiment thereof.

The controls shown in broken lines in FIGS. 1, 8, 15 and 16, form no part of the claimed design.
